UNITED STATES PATENT OFFICE

154,094

DESIGN FOR AN EARRING RACK

Kenneth R. Armstrong, Battle Creek, Mich.,
assignor by decree of court to Catherine C.
Armstrong

Application February 17, 1948, Serial No. 144,548

Term of patent 14 years

(Cl. D80—9)

To all whom it may concern:

Be it known that I, Kenneth R. Armstrong, a citizen of the United States, residing at Battle Creek, in the county of Calhoun and State of Michigan, have invented a new, original, and ornamental Design for Earring Racks, of which the following is a specification, reference being had to the accompanying drawing, forming part thereof.

The figure is a perspective view of an earring rack, showing my new design.

I claim:

The ornamental design for an earring rack, substantially as shown.

KENNETH R. ARMSTRONG.
